(57) **CLAIM**

The ornamental design for a portable male urinal, as shown and described.

DESCRIPTION

FIG. 1 is a front perspective view of a portable male urinal, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of measuring indicia of the portable male urinal is for the purpose of illustrating environmental structure and forms no part of the claimed design.
